Primary Examiner — Lakiya G Rogers*Assistant Examiner* — Altaira J Swangin(74) *Attorney, Agent, or Firm* — Zagorin Cave LLP; Robert W. Holland(57) **CLAIM**

We claim the ornamental design for an information handling system, as shown and described.

DESCRIPTION

FIG. 1 is a front perspective view of the information handling system comprising the present invention; FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof; and,

FIG. 8 is a front perspective environmental view thereof. Broken lines shown in the drawings illustrate portions of the information handling system and form no part of the claimed design. The broken lines, showing the rest of the information handling system in FIG. 8 illustrate environment and form no part of the claimed design.

1 Claim, 6 Drawing Sheets(56)
